CLAIM

The ornamental design for a portable light, as shown and described.

DESCRIPTION

FIG. 1 is a perspective view of a first version of the portable light showing my new design;

FIG. 2 is a top plan view thereof;

FIG. 3 is a bottom plan view thereof;

FIG. 4 is a side elevational view thereof; and

FIG. 5 is an elevational end view thereof;

FIG. 6 is a perspective view of a second version of the portable light showing my new design;

FIG. 7 is a top plan view thereof;

FIG. 8 is a bottom plan view thereof;

FIG. 9 is a first elevational end view thereof;

FIG. 10 is a side elevational end view thereof; and

FIG. 11 is a second elevational end view thereof;

FIG. 12 is a perspective view of a third version of the portable light showing my new design;

FIG. 13 is a top plan view thereof;

FIG. 14 is a bottom plan view thereof;

FIG. 15 is a side elevational view thereof; and,

FIG. 16 is an elevational end view thereof.
